CLAIM

The ornamental design for a pivotal connection for a tool box, as shown and described.

DESCRIPTION

FIG. 1 is a perspective view of the pivotal connection showing my new design;

FIG. 2 is a front view thereof;

FIG. 3 is a rear view thereof;

FIG. 4 is a left side view thereof;

FIG. 5 is a right side view thereof;

FIG. 6 is a top plan view thereof;

FIG. 7 is a bottom view thereof;

FIG. 8 is an illustration when the pivotal connection for a tool box is in use thereof; and,

FIG. 9 is another illustration when the pivotal connection for a tool box is in use.

The broken lines in the drawing are for illustrative purposes only and form no part of the claimed design.
